TRANSPARENT SHAVING CREAM

George M. Naimark, Cleveland, Ohio

No Drawing. Application September 30, 1953
Serial No. 383,395

1 Claim. (Cl. 167—85)

This invention relates to a shaving preparation and particularly to a shaving cream of the brushless type taking the form of a spreadable jelly that is transparent in color and therefore especially useful to a person having facial blemishes of a kind that should be avoided in shaving.

Shaving creams of the types known to the prior art are usually formulated as solutions or suspensions of soaps, although they frequently contain numerous other ingredients. In general, shaving preparations of the lathering type make use, among other things, of soluble and semi-soluble salts of fatty acids dissolved or dispersed in water or at least in an aqueous vehicle. In brushless shaving preparations, on the other hand, the physical nature of the composition is usually that of an emulsion. In neither case is the preparation in any sense transparent and, in consequence, skin blemishes are not revealed but concealed with the result that the razor is too often brought into inadvertent contact with them.

One of the principal objects of the present invention is to provide a shaving cream of the brushless type that is transparent or water-white in color, thus permitting of its application to and use on the face without regard to the location of skin blemishes and permitting of easy trimming of side-burns, mustaches, goatees and the like. A further object of the invention is to provide a shaving cream taking the form of a spreadable jelly that has beard-softening properties, is readily soluble in water, and may easily be rinsed from razor, hands and face. Other objects and advantages of the invention will be apparent from the description which follows, which sets forth representative formulae for transparent shaving creams of the kind to which the invention relates.

A suitable formula for making a transparent shaving cream is the following, in which the concentrations, expressed in terms of percentages by weight, are approximate:

	Percent
Sodium carboxymethyl cellulose (technical grade)	2.5-3.5
Glycerol	5.0
Butyl parahydroxybenzoate	0.025
Perfume	q. s.
Water	q. s.

In making up the composition, the sodium carboxymethyl cellulose is dissolved in water, after which the other ingredients are added in any desired order.

The formula as set forth may, if desired, be modified to include from 0.50% to 1.5% of a standard wetting agent of one of the types usually considered to be non-irritating to normal skin.

A second formulation suitable for such a shaving cream, likewise transparent, is the following:

	Percent
Sodium carboxymethyl cellulose (pharmaceutical grade)	1.5 to 2.5
Propylene glycol	5.0
Methyl parahydroxybenzoate	0.15
Wetting agent	0.5
Perfume	q. s.
Water	q. s.

2

A third formulation giving a water-white jelly suitable for use as a brushless shaving cream is as follows:

	Percent
Sodium carboxymethyl cellulose (pharmaceutical grade)	2.0 to 3.0
Glycerol	10.0
Butyl parahydroxybenzoate	0.025
Wetting agent	0.5
Perfume	q. s.
Water	q. s.

Still a fourth formulation for a spreadable jelly of this kind is shown below:

	Percent
Sodium carboxymethyl cellulose (technical or pharmaceutical grade)	1.5 to 3.5
D-sorbitol	10.0
Chlorobutanol	0.5
Wetting agent	0.5
Perfume	q. s.
Water	q. s.

In each of the foregoing instances, the wetting agent may be any conventional wetting agent of a kind that can be used on the skin without producing undesirable side reactions.

Although in the foregoing formulations the ingredient lending most of the viscosity to the final composition is sodium carboxymethyl cellulose, it is not necessary that this ingredient, to the exclusion of others of the

30 same general type, be the one employed. Other alkali carboxyalkyl cellulose ethers may be considered as, for example, potassium carboxymethyl cellulose, potassium carboxyethyl cellulose, sodium carboxyethyl cellulose, and the corresponding propyl and butyl compounds.

35 Alkali carboxymethyl cellulose ethers of the kinds best meeting the requirements of the invention have, in general, an average substitution of about 0.7 alkali carboxymethyl radicals for each anhydroglucose unit of the cellulose structure, although the degree of substitution can vary considerably from this level and may in some instances go as high as 1.3.

With sodium carboxymethyl cellulose of approximately 0.7 substitution, the ether will ordinarily be of the high viscosity type if the concentration is to be in the range 45 from 1.5% to 3.5%. In such case, a 1% solution in water (by weight) should ordinarily have a viscosity from about 1300 to about 2200 centipoises when measured at 25° C. with a rotating spindle viscometer of the Brookfield type. At higher concentrations, however, ethers of 50 middle and low viscosity types may be used.

Alkali carboxyalkyl celluloses of the kinds described have a pronounced affinity for water. Although they are mixtures rather than pure compounds, they dissolve readily to form what appear to be crystal-clear solutions.

55 The latter are more accurately described as colloidal suspensions in which no discrete particles are visible to the naked eye. In describing them, it is usual to refer to them as solutions, particularly since the addition of more water, as in rinsing, disperses them with unusual rapidity. 60 As a result of this property, a shaving cream formulated as hereinabove described will be found to disappear promptly from razor, hands and face when subjected to rinsing.

The humectant, occurring in the preparation as but a minor fraction but nevertheless in an amount which, by weight, is several times that of the sodium carboxymethyl cellulose, may vary from something below 5% to something above 10% by weight of the preparation as a whole. It is added for the most part to keep the shaving preparation from drying on the face; however, to some extent it does have an emollient action. When a humectant is present along with water, sodium carboxymethyl cellulose

and a wetting agent, the resulting combination, if used as a shaving preparation, has a tendency to soften the beard after the natural oils have once been removed, as by a preliminary washing. In general, a great many of the commercially available humectants that are considered to be non-irritating to normal skin may be used, as, for example, the glycerols, glycols, sorbitols, and a considerable number of other well-known humectants.

If a wetting agent is used, it may be almost any commercial wetting agent that may be safely employed on the skin. An example is the polyoxyethylene sorbitan monolaurate product supplied by the Atlas Powder Company under the trademark "Tween 20." Such an ingredient, if used, will tend to improve not only the wetting properties but also the spreading properties, beard-softening tendency and what may be called the rinsability of the preparation as a whole. The normal concentration of the wetting agent will usually range between 0.5% and 1.5%, although it may be more or less.

Depending somewhat on the concentration of the sodium carboxymethyl cellulose, a preservative may or may not be necessary from a theoretical standpoint, but as a practical matter one will usually be present. In general, solutions containing less than 4% of sodium carboxymethyl cellulose are susceptible to attack by bacteria, resulting in a lowering of the viscosity. Mold growth may occur even in more concentrated solutions which are stored for long periods of time. Therefore, to inhibit mold and bacteria growth, it is advantageous to add a preservative of a kind that can be safely employed upon normal skin, as, for example, methyl parahydroxybenzoate, propyl parahydroxybenzoate, butyl parahydroxybenzoate, sodium benzoate, potassium benzoate, chlorobutanol and, to the extent that they are soluble in water, other generally similar preservatives. Preservatives of kinds known to be toxic are of course to be avoided.

The perfume may be any appropriate water-soluble perfume in any amount that is sufficient to be effective.

It will be noted that in the foregoing formulations the sodium carboxymethyl cellulose is present in a very small amount, generally from 1.5% to 3.5% by weight of the preparation, although the preferred range is usually between 2.5% and 3.5%. Notwithstanding the fact that it is present in such a small amount, the ether contributes the viscosity which gives the jelly-like character to the preparation. Ethers of the kinds described tend somewhat to lower the surface tension of water, although this lowering is not ordinarily so significant as to preclude the desirability of adding the wetting agent. At certain concentrations, solutions of sodium carboxymethyl cellulose sometimes tend to show thixotropic characteristics: if present, this tendency may give the shaving preparation a temporary stiffness which will not preclude its easy application to the face.

Both technical and purified (99%) grades of sodium carboxymethyl cellulose may be used, although with the former precautions sometimes have to be taken in processing to improve the clarity and avoid a tendency to graininess in the product.

The pH of the final preparation should preferably be upwards of 6, as in the range between 6 and 9, but preferably about 7. In this bracket, preparations of the kind described are not irritating to normal skin, but if the pH is permitted to go much above 9 or too far below 6 a tendency to irritation of sensitive skins may manifest itself.

In this connection, it is desirable that the added ingredients, particularly the preservative, be of a nature such as not to vary the pH unduly. In general, the pH of solutions of sodium carboxymethyl cellulose is easy to control, being ordinarily from 6 to 8.

Thus the invention provides a unique shaving preparation having the advantage of being limpid or water-white

in color and permitting of use where facial blemishes constitute a complicating factor. Although taking the physical form of a colloidal suspension rather than a true solution, it is highly stable. Preparations of the kinds described are not emulsions and will not break down or discolor notwithstanding temperature changes over a wide range, although any increase in the temperature above ordinary room temperatures tends to decrease the viscosity until the temperature is reduced. An important advantage is the ease with which consistency can be controlled: slight changes in the concentration of the sodium carboxymethyl cellulose will control consistency so that the preparation will not flow from a collapsible tube without pressure, will not require excessive pressure to extrude it from such a tube, and will not lose its form upon being released from the tube.

These preparations can stand for years without deleterious consequences even though in intimate contact with aluminum, tin and other metals, as in collapsible tubes and/or the common types of metal cap liners. Compounded as suggested above, the preparations have substantial lubricating properties but are so readily dispersible in water that they can easily be rinsed from the razor, hands and face. Being soapless, alkali-free and free of fatty acids, they are neutral or nearly and chemically inert. They are also physiologically inert; i. e., non-irritating, not toxic if taken internally, and safe if they fall into the hands of children.

It is intended that the patent shall cover, by suitable expression in the appended claim, all features of patentable novelty that reside in the invention.

What is claimed is:

A transparent shaving preparation of the brushless type taking the form of a water-white easily spreadable jelly consisting, in parts by weight, of 1.5% to 3.5% of a pharmaceutical grade sodium carboxymethyl cellulose of the high viscosity type characterized by a degree of hydroxyl substitution per anhydroglucose unit of less than about 1.3, 5% to 10% of a polyol selected from the group consisting of glycerol, propylene glycol and d-sorbitol, 0.5% of a surface-active agent having beard-softening properties, a cosmetic preservative, soluble in water, in quantity sufficient to be effective, and water as needed to make up the balance, the jelly being transparent, physiologically inert, devoid of graininess, free of any tendency to attack common metals, of a consistency such that it will not only flow from a collapsible tube under pressure but will maintain its form upon being released from the tube, and characterized by a pH in the range between 6 and 9.
